PISTON RING

Carl F. Engelhardt, Yeadon, Pa., assignor to
Wilkening Manufacturing Company, Philadelphia, Pa.

Original application May 19, 1942, Serial No.
443,601. Divided and this application November 8, 1943, Serial No. 509,353

9 Claims. (Cl. 309—45)

The present invention relates to certain new and useful improvements in piston rings and it relates more particularly to oil-control piston rings adapted for use in internal combustion engines.

The present application is a division of my co-pending application Serial No. 443,601, filed May 19, 1942.

An object of the present invention is to provide a simple, inexpensive and efficient piston-ring for use in internal combustion engines. Another object of the present invention is to provide a piston-ring formed of a strip of sheet metal or the like suitably bent and folded to provide an interlocked composite structure having continuous axially-separated cylinder-contacting ribs and having oil-drain passages therethrough.

Other objects and advantages of the present invention are apparent in the following specification, appended claims and accompanying drawing.

For the purpose of illustrating the invention, there are shown in the accompanying drawing forms thereof which are at present preferred, since the same have been found in practice to give satisfactory and reliable results, although it is to be understood that the various instrumentalities of which the invention consists can be variously arranged and organized and that the invention is not limited to the precise arrangements and organizations of the instrumentalities as herein shown and described.

Referring to the accompanying drawing in which like reference characters indicate like reference parts throughout:

Figure 1 represents a perspective view of one embodiment of the present invention as it appears when dis-assembled and helically extended.

Figure 2 represents a fragmentary edge elevational view of the embodiment of Figure 1, showing the zone of "cross-over" forming the junction of the upper and lower turns of the helix as it appears when the ring is assembled.

Figure 3 represents a cross-sectional view generally along the line 3—3 of Figure 2 showing the appearance of the piston-ring when installed upon a piston.

Figure 4 represents a cross-sectional view generally along the line 4—4 of Figure 2.

Figure 5 represents a cross-sectional view generally similar to that of Figure 4 but showing a modified form of the present invention.

In the embodiment of Figures 1 to 4, I may

provide a piston-ring formed of a single helical strip of sheet metal or the like having two complete turns. The helical strip is provided with alternating upper segments 41 and lower segments 42 extending in generally horizontal axially-displaced planes. Successive segments 41 and 42 are connected by generally axially-extending portions 43 which are formed integrally with, and at obtuse angles to, the horizontally-extending segments 41 and 42.

The axially-extending portions 43—a of one complete turn (as for example the upper turn shown in Figure 1) of the strip 40 are cut out as at 44 along their inner peripheral edges for slightly more than half the radial dimension thereof. The axially-extending portions 43—b of the other turn (as for example the lower turn shown in Figure 1) of the strip 40 are cut out as at 45 along their outer peripheral edges for slightly more than half the radial dimension thereof.

The horizontal cross-over segment 46 integrally connects the two turns of the strip 40 and has one axially-extending portion 43—a cut out along the inner peripheral edge as at 44 and the other axially-extending portion 43—b cut out along the outer peripheral edge as at 45; the segment 46 thereby effecting the transition from the construction of one turn to the construction of the other turn of the member 40.

The member 40 assumes the helical form shown in Figure 1, when its free ends 47 and 48 are spread axially apart. Whenever, however, the free ends 47 and 48 are released, the natural resiliency of the member 40 causes it to spring together. If the cross-over segment 46 is then pressed radially inwardly, the upper and lower turns will dove-tail within each other to provide the generally closed construction shown in Figures 2, 3 and 4. That is, the axially-extending portions 43—b of the lower turn fit within the cut-out edges 44 of the portions 43—a while the portions 43—a fit within the cut-out edges 45 of the portions 43—b. As shown in Figure 2, the portions 43—a and 43—b are oppositely inclined in the inter-nested position of the member 40.

In the assembled position shown in Figures 2, 3 and 4, the upper segments of the upper and lower turns are in alternating juxtaposition and, similarly, the lower segments of the upper and lower turns are in alternating juxtaposition to provide a pair of axially-displaced more or less continuous cylinder-contacting ribs.

A plurality of circumferentially-spaced radially-extending oil passageways 49 are provided intermediate the cylinder-contacting ribs and are defined by the upper and lower horizontal segments 41 and 42 and the radially-spaced axially-extending portions 43—a and 43—b.

The free ends 47 and 48 may be seated against each other in any suitable manner as for example in the manner shown in Figure 2 wherein the free ends are placed radially adjacent to each other and terminate axially adjacent the crossover segment 46.

The fold-lines separating the segments from the axially-extending portions are preferably formed as sharp edges by coining or other suitable operations whereby the adjacent segments will make firm and continuous contact with each other as shown particularly in Figure 2 to provide a generally fluid-tight seal therebetween. When the piston-ring is assembled within the groove 34 of a piston 35 and is installed within a cylinder 36 as shown in Figure 3, the piston-ring is compressed slightly both radially and circumferentially; the ring having inherent resiliency whereby it will tend to expand radially and circumferentially against the cylinder wall and to make firm contact therewith without the use of a separate expander spring.

The radially-adjacent axially-extending portions 43—a and 43—b have a slight clearance 39 radially therebetween whereby the upper and lower turns are free to move axially and radially of each other to a limited extent, thereby to permit the piston-ring better to conform to any irregularities in the cylinder wall such as might be caused by wear.

A modified form of the present invention is shown in Figure 5 wherein the outer peripheral edges of the axially-extending portions 43—a are cut away as at 20—b so that the axially-extending portions 43—a are recessed slightly from the edges of the upper and lower segments 41 and 42. Thus, when the piston-ring is finally assembled, it makes contact with the cylinder wall only along the axially-spaced, more or less continuous, annular ribs formed by the juxtaposed upper and lower segments.

This embodiment may, in some respects, be preferred since the contact area between the piston and the cylinder is reduced, thus giving a greater unit pressure to reduce "blow-by" and, at the same time, to reduce wear.

The present invention may be embodied in other specific forms without departing from the spirit or essential attributes thereof, and it is therefore desired that the present embodiments be considered in all respects as illustrative and not restrictive, reference being had to the appended claims rather than to the foregoing description to indicate the scope of the invention.

Having thus described the invention, what is hereby claimed as new and desired to be secured by Letters Patent is:

1. A piston-ring comprising a helical strip of ribbon-like sheet metal having at least two complete turns, said strip being axially non-sinuously corrugated to provide successive plane segments disposed alternately in axially-separated radial planes and generally axially-extending interconnecting portions formed integrally with said segments, said strip being disposed in axially-collapsed radially-nested position with the interconnecting portions of each turn disposed in intercrossing relationship to provide circumfer-

entially distributed radially-extending oil-passageways.

5 2. A piston-ring comprising a helical strip of ribbon-like sheet metal having at least two complete turns, said strip being axially non-sinuously corrugated to provide successive plane segments disposed alternately in axially-separated radial planes and generally axially-extending interconnecting portions formed integrally with said segments, the interconnecting portions of one turn of said strip being radially-displaced from the interconnecting portions of the other turn of said strip, said strip being disposed in axially-collapsed radially-nested position with the interconnecting portions of the respective turns being radially juxtaposed in intercrossing relationship.

10 3. A piston-ring comprising a helical strip of ribbon-like sheet metal having at least two complete turns, said strip being axially non-sinuously corrugated to provide successive plane segments disposed alternately in axially-separated radial planes and generally axially-extending interconnecting portions formed integrally with said segments, the interconnecting portions of one turn of said strip being radially-displaced from the interconnecting portions of the other turn of said strip, said strip being disposed in axially-collapsed radially-nested position with the interconnecting portions of the respective turns being radially juxtaposed in intercrossing relationship.

15 4. A piston-ring comprising a helical strip of ribbon-like sheet metal having at least two complete turns, said strip being axially non-sinuously corrugated to provide successive plane segments disposed alternately in axially-separated radial planes and generally axially-extending interconnecting portions formed integrally with said segments, the interconnecting portions of one turn of said strip being radially-displaced from the interconnecting portions of the other turn of said strip, said strip being disposed in axially-collapsed radially-nested position with the interconnecting portions of the respective turns being radially juxtaposed in intercrossing relationship, the plane segments of the respective turns being arranged in alternating juxtaposition to provide a pair of more or less continuous annular axially-separated cylinder-contacting ribs.

20 5. A piston-ring comprising a helical strip of ribbon-like sheet metal having at least two complete turns, said strip being axially non-sinuously corrugated to provide successive plane cylinder-contacting lands disposed alternately in axially-separated radial planes, and generally axially-extending interconnecting portions formed integrally with said lands, the interconnecting portions of one turn of said strip being radially spaced apart from the interconnecting portions of the other turn, said strip being disposed in axially-collapsed radially-nested position, thereby to provide a pair of more or less continuous annular axially-separated cylinder-contacting ribs having oil-passageways therebetween.

25 6. A piston-ring comprising a helical strip of ribbon-like sheet metal having at least two complete turns, said strip being axially non-sinuously corrugated to provide successive plane cylinder-contacting lands disposed alternately in axially-separated radial planes, and generally axially-extending interconnecting portions formed integrally with said lands, the interconnecting portions of one of said turns being disposed adjacent the outer edge of the piston-ring and the interconnecting portions of the other of said turns being disposed adjacent the inner edge of the piston-ring, said strip being disposed in axially-collapsed radially-nested position, thereby to provide a pair of more or less continuous annular axially-separated cylinder-contacting ribs having oil-passageways therebetween.

30 7. A piston-ring comprising a helical strip of ribbon-like sheet metal having at least two complete turns, said strip being axially non-sinuously corrugated to provide successive plane cylinder-contacting lands disposed alternately in axially-separated radial planes, and generally axially-extending interconnecting portions formed in-

tegrally with said lands, the interconnecting portions of one of said turns being disposed adjacent the outer edge of the piston-ring and the interconnecting portions of the other of said turns being disposed adjacent the inner edge of the piston-ring, the interconnecting portions of the first-mentioned turn being recessed somewhat along their outer edges from the outer edges of the lands, said strip being disposed in axially-collapsed radially-nested position, thereby to provide a pair of more or less continuous annular axially-separated cylinder-contacting ribs having oil-passageways therebetween.

7. A piston-ring comprising a helical strip of ribbon-like sheet metal having at least two complete turns, said strip being axially non-sinuously corrugated to provide successive plane cylinder-contacting lands disposed alternately in axially-separated radial planes, and generally axially-extending interconnecting portions formed integrally with said lands, the interconnecting portions of one of said turns being disposed adjacent the outer edge of the piston-ring and the interconnecting portions of the other of said turns being disposed adjacent the inner edge of the piston-ring, the interconnecting portions of the first-mentioned turn having their outer edges recessed somewhat from the outer edges of the lands and having their inner edges recessed somewhat from the outer edges of the interconnecting portions of the other turn, said strip being disposed in axially-collapsed radially-nested position, thereby to provide a pair of more or less continuous annular axially-separated cylinder-contacting ribs having oil-passageways therebetween.

8. A piston-ring comprising a helical strip of ribbon-like sheet metal having at least two com-

plete turns, said strip being axially non-sinuously corrugated to provide successive plane segments disposed alternately in axially-separated radial planes and generally axially-extending interconnecting portions formed integrally with said segments, said strip being disposed in axially-collapsed radially-nested position with the interconnecting portions of each turn disposed in intercrossing relationship to provide circumferentially distributed radially-extending oil-passageways, said strip having a double-length plane segment intermediate successive turns.

9. A piston-ring comprising a helical strip of ribbon-like sheet metal having at least two complete turns, said strip being axially non-sinuously corrugated to provide successive plane cylinder-contacting lands disposed alternately in axially-separated radial planes, and generally axially-extending interconnecting portions formed integrally with said lands, the interconnecting portions of one of said turns being disposed adjacent the outer edge of the piston-ring and the interconnecting portions of the other of said turns being disposed adjacent the inner edge of the piston-ring, the interconnecting portions of the first-mentioned turn being recessed somewhat along their outer edges from the outer edges of the lands, said strip being disposed in axially-collapsed radially-nested position, thereby to provide a pair of more or less continuous annular axially-separated cylinder-contacting ribs having oil-passageways therebetween, said strip having a double-length plane cylinder-contacting land intermediate successive turns whereby the upper and lower lands of one turn are circumferentially displaced from the corresponding lands of the other turn.

CARL F. ENGELHARDT.
